UNITED STATES PATENT OFFICE.

ARTHUR E. WYMAN, OF SPRINGFIELD, MASSACHUSETTS.

METHOD OF COVERING OBJECTS WITH SHEET-PYROXYLIN.

No. 892,702.

Specification of Letters Patent.

Patented July 7, 1908.

Application filed July 23, 1907. Serial No. 385,206.

To all whom it may concern:

Be it known that I, ARTHUR E. WYMAN, a citizen of the United States of America, and resident of Springfield, in the county of 5 Hampden and State of Massachusetts, have invented certain new and useful Improvements in Methods of Covering Objects with Sheet-Pyroxylin, of which the following is a full, clear, and exact description.

10 This invention relates to the manufacture of articles having a covering of sheet pyroxylin material, such as popularly known as sheet celluloid, and the object is to perform the covering operation in such a manner as to 15 eliminate much of the labor and the requirement of considerable and expensive apparatus and appliances heretofore required.

In the covering operation as heretofore practiced and also as now practiced by me, 20 the sheet pyroxylin material brought directly to contact against the article to be surfaced thereby is rendered plastic by heat, and then by a suitably applied pressure it is forced to conform and adhere to the contour, 25 however irregular, of the object.

As heretofore practiced in a somewhat extensive, and a practical, way the object to be covered is placed in a flexible rubber bag, which is capable of being tightly closed, together with the pyroxylin sheet material in 30 contact thereagainst and in some cases partially or loosely wrapped around the object. The bag, closed, is placed and closed in a cylindrical receptacle, termed in shop parlance 35 a "gun", into which very hot water under a considerable hydraulic pressure is introduced and maintained with the effect of collapsing the rubber bag, and through the medium of the latter, which will be constricted to the 40 contour of the inclosed object therewithin, force the sheet material,—rendered plastic by the hot water through the bag as a heat conductor,—to close adherence and conformation to the contour of the object to be 45 covered, or so much thereof as desired to be covered, a cement being used for holding the covering on the object, the application of the same being made preparatory to introducing the parts into the rubber bag. The so called 50 "gun" and the means for establishing a suitably high pressure of the hot water therein are expensive, and yet an even greater cost consideration is that for the rubber bags

which have but a short life, quickly deteriorate from the effects of the hot water, and 55 are useless when ruptured or having a puncture even as minute as a pin hole.

The present invention consists in the method of covering an object with sheet pyroxylin material, consisting in disposing the 60 object and sheet material one next to the other in an inclosed receptacle, rendering the sheet material plastic by heat, and subjecting the plastic sheet material to the action of 65 confined air, under pressure directly effective thereon for deflection thereof, whereby such material closely conforms to the contour of, and is made to closely cover, the given object. By this mode of operation the necessary apparatus to be employed is much 70 cheaper than the "gun" and water heating and hydraulic pressure appliances; and the necessity for the expensive and non-durable rubber sacks is entirely avoided.

As an exemplification of the carrying out 75 of my improved method I will, in conjunction with the accompanying drawings, describe the procedure for covering, on its top, and around its internal and external portions, an apertured water closet seat with sheet 80 "celluloid", any suitable or analogous material other than celluloid, or other than any pyroxylin, to be regarded as the equivalent thereof.

Referring to the drawings: Figure 1 is a 85 plan view of the apparatus adequate for the carrying out of the process. Fig. 2 is a vertical sectional view on line 2—2, Fig. 1, showing the section of a water closet seat and the covering sheet material in place in the closed 90 receptacle and in readiness to be subjected to the action whereby the sheet material is made to conform to the contour of the seat. Fig. 3 is a view similar to Fig. 2, but showing the result of the action for the conformation of the sheet material at the seat. Fig. 4 is a vertical sectional view through the seat with an additional covering on the bottom thereof. Figs. 5 and 6 are views herein-after referred to relating to the covering by 100 celluloid of a cross sectionally round object.

A represents an iron box made in separable sections a and a^2 with clamping means for detachably holding the box closed in air tight condition, a packing at the meeting 105 edges of the box being provided if desired.

In the lower box section is a raised portion upon which the object to be covered rests, and for the purpose of illustration the lower box section is shown provided with an annular rib *d* upon which a water closet seat *w* is shown.

B represents a steam pipe-coil provided within and supported by the upper section, a portion of the connected and throttle-valve-
10 provided supply-pipe being represented at *b*.

D represents a sufficient portion of a valve-provided pipe connected into the upper box section and understood as having connection with any ordinary air compressor, (not shown).

The box *A* being opened the seat *w* is placed on the rest or supporting rib *d*, and a sheet *x* of "celluloid", having a superficial area greater than that of the seat, and in fact 20 fully as great as the box, (either the seat or the sheet being surfaced with celluloid cement) is laid while in flat condition upon the seat, and with its marginal portions overlying the upper edge of the lower box section *a*. The 25 box is then closed by bringing the box section *a*² to place and fastening it so as to clamp the marginal portions of the sheet in the manner represented in Fig. 2, whereby, as will be clearly understood, the sheet constitutes a diaphragm between the upper and lower halves of the box chamber.

The steam is turned on, and the air under pressure, say, of 25 pounds to the square inch, or more or less as desirable or necessary, is admitted with the result that the air heated by the steam within the box, softens the sheet material,—the same becoming plastic and capable of being expanded,—and forced by the air pressure, in the chamber of 40 which the celluloid diaphragm *x* is the lower boundary, to close conformation to the contour of the seat,—this latter condition or relations of the parts being substantially as represented in Fig. 3, wherein it will be perceived that a portion *x*² of the sheet material is forced below the plane of the under surface of the seat and remains as a spanning continuation of the dished portions of the thin pyroxylin which covers the flaring wall of the 50 seat aperture. The cement preferably employed in the operation of this process hardens after application, and is softened and rendered viscous by heat, and this softening is more effectually accomplished by the effect 55 of hot air in an inclosed chamber, as shown in the improved process herein described. Cement of the character employed can thus be applied to the article to be covered at any time and permitted to dry thereon, and is 60 readily rendered operative when the heat necessary to soften the covering material is applied. It will also be perceived that the seat edges are covered with the sheet material, conformed and adherent thereto, while,

incidentally under the pressure of the air at 65 one side of the sheet only, the sheet between the seat edges and the box walls is downwardly deflected, as indicated at *x*³ in Fig. 3.

The box being opened and the covered seat removed, the portions *x*² and *x*³ are sheared or trimmed off flush with the lower surface of the seat, and then an additional covering sheet of the pyroxylin may be provided on the under side of the seat, as represented at *y* in Fig. 4, making use of the described apparatus for applying it, or performing the operation otherwise, as preferred.

This method is equally available for celluloid-covering objects having greater irregularity than water closet seats, as will be obvious.

In Fig. 6, and the cross section thereof, Fig. 5, a cross sectionally round article is represented which may be covered with sheet celluloid:—the celluloid sheet *x* is wrapped 85 more or less closely about the object *w*²,—cement having been applied on the object, or on the proximate surface of the covering material,—and upon being placed and inclosed within the box *A* having the equipments described, whereby the heated air therein renders the wrapping sheet plastic, the air under compression is forced into the chamber, with the effect of causing a constriction of the celluloid wrapping so that it adheres to, and 95 has a conformation to the contour of the object.

I claim:—

1. The method of providing a water closet seat with a sheet of pyroxylin, which consists 100 in disposing the seat right side up with a sheet of pyroxylin material supported on the seat in a closed receptacle, and subjecting the pyroxylin material on the outer side to the action of heated dry air under pressure to 105 effect a softening and consequent expansion and deflection of the material into intimate permanent engagement with the outer wall of the seat and the wall of the seat aperture.

2. The method of providing an object having 110 an irregular contour with an attached covering sheet of pyroxylin material conformed to such contour, which consists in disposing the object with a sheet of pyroxylin material with a cement between them in a 115 closed receptacle, and subjecting the pyroxylin material on the outer side to the action of heated dry air under pressure to effect a softening of the material and the cement and a consequent expansion and deflection of the 120 material into intimate permanent engagement with the object.

3. The method of providing an object having 125 an irregular contour with an attached covering sheet of pyroxylin material conformed to such contour, which consists in disposing the object with a sheet of pyroxylin material with a cement between them in a

closed receptacle, marginally confining the sheet in said receptacle, whereby it constitutes a chamber partitioning diaphragm therein, and subjecting the pyroxylin material on the outer side and within its confined margins to the action of heated dry air under pressure to effect a softening of the material and the cement and a consequent expansion

and deflection of the material into intimate permanent engagement with the object. 10

Signed by me at Springfield, Mass., in presence of two subscribing witnesses.
